United States Patent Office

Des. 191,860
Patented Dec. 5, 1961

191,860

LAVATORY BOWL

Henry A. Holberson, Youngstown, Ohio, assignor to The Youngstown Sheet and Tube Company, Youngstown, Ohio, a corporation of Ohio

Filed May 25, 1961, Ser. No. 65,333

Term of patent 14 years

(Cl. D4—2)

Fig. 1.

Fig. 2.

Fig. 3.

Fig. 4.

FIG. 1 is a perspective view of a lavatory bowl showing my new design;

FIG. 2 is a top plan view of the lavatory bowl shown in FIG. 1 on a reduced scale;

FIG. 3 is a front elevation on the same scale as FIG. 2, and

FIG. 4, likewise on the same scale as FIG. 2, is a side elevation of the bowl looking from the right in FIG. 3.

I claim:

The ornamental design for a lavatory bowl, as shown.
